UNITED STATES PATENT OFFICE.

ALBERT V. BIGWOOD, OF SCOTIA, AND LOUIS KOZELEK, OF SCHENECTADY, NEW YORK.

ROTARY TOOTHBRUSH.

Application filed February 17, 1921. Serial No. 445,635.

To all whom it may concern:

Be it known that we, (1) ALBERT V. BIGWOOD, a citizen of the United States of America, and (2) LOUIS KOZELEK, a citizen 5 of Czechoslovakia, residing at (1) Scotia and (2) Schenectady, in the county of Schenectady and State of New York, have invented certain new and useful Improvements in Rotary Toothbrushes, of which

10 the following is a specification:

This invention relates to a certain new and useful improvements in rotary toothbrushes and the principal object of the invention is to provide a brush of this kind 15 in which the brush element per se is specifically formed to snugly engage the face of the teeth for efficiently cleaning the same when the brush is rotated, the brush being provided with a shank operable for rotat- 20 ing it.

A further object of the invention is to provide the shank with a sleeve adapted to be grasped between the fingers of the user so as to effectively support the brush while 25 it is rotated, the shank being rotatable in the sleeve.

A still further object of the invention is to provide a novel rotatable brush including a brush member and a two-part shank, with 30 quick detachable means for connecting the parts of the shank, whereby various forms of brushes or new ones may be utilized from time to time.

Further objects will appear as the nature 35 of the invention is better understood, and the same consists in the novel form, combination and arrangement of parts herein-after more fully described, shown in the accompanying drawing and claimed.

40 In the drawing wherein like reference characters designate corresponding parts throughout the several views,

Figure 1 is a view partly in side elevation and partly in longitudinal section of 45 one form of tooth brush constructed in accordance with the present invention,

Figure 2 is an end view thereof,

Figure 3 is a transverse sectional view taken upon line III—III of Fig. 4,

50 Figure 4 is a side elevational view of a modification of the invention,

Figure 5 is a side elevational view of the brush element and its shank part detached, of the brush shown in Fig. 4,

55 Figure 6 is a transverse sectional view taken upon line VI—VI of Fig. 4, and

Figure 7 is a similar view taken upon line VII—VII of Fig. 4.

Referring more in detail to the drawing, in the form of the invention shown in Figs. 60 1 to 3 inclusive, the brush comprises a brush member per se 5 composed of closely related radically projecting fibres or bristles, providing a brush element in the form of a 65 concave cylinder, said fibres being suitably placed upon the outer end of a straight shank 6 having its opposite end portion enlarged and of angular form as at 7, said shank projecting axially from the brush element 5. A sleeve 9 is loosely positioned 70 upon the intermediate portion of the shank 6 so as to be longitudinally movable thereon, the shank also being revoluble within said sleeve.

In the operation of this form of the invention, the sleeve 9 is grasped by the operator in one hand so as to support the brush element 5 properly with relation to the teeth, and the operator then rotates the shank 6 by proper manipulation of the angular portion 7 with the other end. The sleeve 9 may be moved toward or away from the brush element 5 as the requirements suggest for most conveniently using the invention.

80 In the form of the invention shown in Figs. 4 to 7 inclusive, the brush element 5' is provided with the axial shank part or section 6' and is of the same form as described with respect to the brush element 90 5 in Figs. 1 to 3 inclusive. The free end of the shank section 6' is formed with a head 10 adapted for detachable reception within a spring socket 11 provided on one end of a further shank section 12, whereby 95 the shank sections 6' and 12 are effectively connected in longitudinal alignment so that when one is rotated the other will rotate therewith, and at the same time permit the detachment of these parts for the renewal 100 of the brush elements from time to time as found necessary or for employing brush elements of different kinds, which may be furnished. The shank section 12 is swiveled at its outer end as at 13 in a knob or hand grip 14, and it is also provided with reverse quick threads or grooves 15 which intersect and which are engaged by the inwardly 105 projecting end of a pin 16 which projects into the bore of a sleeve 17. The sleeve 110 17 is longitudinally movable on the shank section 12, and the latter is rotatable in said

sleeve, while the pin 16 is detachably carried by the sleeve 17 as shown in Fig. 7.

In the operation of this form of the invention, the sleeve 17 is substantially uniformly reciprocated or given a uniform rectilinear motion and through the construction described, this motion is utilized to give a substantially uniform rotary motion of the parts 12, 6' and 5'. This is done 10 by grasping of the knob 14 in one hand and reciprocating the sleeve 17 with the other.

From the foregoing description it is believed that the construction and operation 15 of the present invention will be readily understood and the advantages thereof appreciated by one skilled in the art.

What is claimed as new is:—

In a rotary brush of the type described, 20 a cylindrical brush member, a shank carried by said brush and axially alined therewith, a head formed upon the free end of the shank, a second shank having a pair of thread grooves arranged in reverse direc-

tions and intersecting at spaced points, 25 a resilient socket formed on one end of the second shank for receiving said head with both shanks axially alined and connected so that when one is rotated the other will rotate therewith, the said head and 30 resilient socket being axially alined with both shanks, a handle loosely mounted upon the second shank, and a sleeve slidably mounted on this second shank and a pin 35 projecting inwardly from the sleeve to engage with said grooves to cause rotation of the brush member, said pin being shiftable by rotative movement of the sleeve from one groove to the other at any point of intersection of said grooves. 40

In testimony whereof we affix our signatures in presence of two witnesses.

ALBERT V. BIGWOOD.
LOUIS KOZELEK.
